CLAIM

I claim the design for a portable toilet with carrying case and detachable shelter pack, as shown and described.

DESCRIPTION

FIG. 1 is a front perspective view of the carrying case and detachable shelter pack showing my new design; FIG. 2 is a top view on a reduced scale of the carrying case in an open position shown separately for clarity of illustration;

FIG. 3 is a front elevational view on a reduced scale of the carrying case in an open position shown separately for clarity of illustration;

FIG. 4 is a side elevational view shown on a reduced scale of the carrying case in an open position and shelter pack before attachment to carrying case, the opposite side being a mirror image thereof;

FIG. 5 is a rear elevational view on a reduced scale of the shelter pack shown separately for clarity of illustration;

FIG. 6 is a rear elevational view of the carrying case showing the contents of the portable toilet and one additional toilet tissue roll in an unassembled condition;

FIG. 7 is a front perspective view on an enlarged scale of the assembled portable toilet;

FIG. 8 is a side elevational view on an enlarged scale of the assembled portable toilet the opposite side being a mirror image thereof; and,

FIG. 9 is a rear elevational view on an enlarged scale of the assembled portable toilet.
